UNITED STATES PATENT OFFICE

CLAUDE DREVET, OF PARIS, FRANCE

MOTOR

Application filed March 26, 1925, Serial No. 18,613, and in France April 4, 1924.

The present invention relates to a motor operating with steam or other fluid under pressure, of the type in which the fluid is admitted between the internal surface of a cylinder rotatably mounted on a stationary shaft and the external surface of a second cylinder rotating on a second stationary shaft parallel to the first-mentioned shaft, the said cylinders being adapted to remain tangent along a fixed line, whereas the crescent shaped space between the cylinders is divided by a sliding plate into two spaces of which the capacity increases and decreases alternately from zero to a maximum during each revolution of the said plate which is actuated by the cylinders.

My invention contemplates a device for variable expansion as well as suitable reversing means, and possesses the following advantages.

20 First: None of the parts serving for the fluid-tight construction are free from movements of transmission, stresses or reactions. Said parts operate freely, and their normal wear as well as the effects of expansion are automatically compensated.

Second: The internal cylinder acts solely as a separator, not a transmitter, i. e. the separating plate is slideable in a slot in the said cylinder without subjecting the guiding means to any reaction due to the pressure. The said plate is preferably pivotally mounted on the external cylinder and may be guided by a rocker bearing on the internal cylinder.

Third: Both cylinders are mounted upon ball or roller bearings.

Fourth: A plurality of internal cylinders are movable within a common external cylinder and the corresponding plates are spaced at suitable angles whereby all dead centre is obviated and the engine can be started at full load.

Fifth: The steam inlet can be regulated at will and is also subjected to the action of a centrifugal governor in such manner that the expansion is proportional to the load, from whence results a very constant speed irrespective of load variation.

Sixth: The steam is admitted to the admission ports through the stationary shaft which is of a hollow construction, which al-

lows easy control of the distribution elements from the exterior and the checking of their positions by experiment for various angular speeds.

Seventh: All the operating elements for the control of the circulation of the power fluid, for regulating the admission and expansion, the speed and power, for reversing the direction of running, and for regulating the lubrication, are placed together in a convenient position upon one side of the machine.

Eighth: Reciprocating motion is entirely eliminated, and the driving elements, which are in opposition as to power and weight, balance each other, thus allowing high speeds to be obtained without jarring.

Ninth: The so-called motor is rotatably mounted within a stationary casing which is filled with the exhaust steam and which may be connected with a condenser.

Tenth: Lubrication can be carried out by a single oiler feeding on the one hand into the steam inlet and on the other hand into the oil ducts leading to the parts exposed to friction or to the bearings.

The appended drawings show by way of example a constructional form of a motor according to the invention comprising two internal cylinders provided with sliding plates spaced at 180°.

Fig. 1 is an axial section of the said motor; and

Figs. 2 and 3 are sections respectively on the lines 2—2 and 3—3 of Fig. 1.

1 is the external cylinder which is provided with a middle partition 2 separating the two internal cylinders 3 and 4. The latter are mounted in eccentric position upon the stationary crank-shaft 5 and rotate in the ball-bearings 28 and 29. This aggregate is disposed in a stationary casing 6 forming a frame and provided with two heads 7 and 8. The said crankshaft is keyed in a permanent manner to the head 8 and has mounted thereon the eccentrics 46 and 47 upon which are respectively revoluble the cylinders 3 and 4. Within the said casing is an exhaust orifice 23 in which may be 100

mounted a conduit leading to the condenser or to the atmosphere.

The cylinder 1 is provided with two heads 9 and 10. The end portion 10 is mounted 5 by means of a bearing 30 upon a suitable flange provided upon the head 8. The head 9 is mounted upon the crankshaft 5 by means of the bearing 31, and carries the distribution conduits (admission and exhaust) and a 10 housing 52 containing the helical non-rotatable valves 13 and 14 serving to regulate the distribution. To the housing 52 is secured the driving shaft 11 provided with a pulley 12, for example, and rotating in a ball-bearing 33. Under the combined action of a 15 centrifugal regulator 25 and a reaction spring 19, the valves 13 and 14 may be given a longitudinal displacement when the motor is running. The periphery of each of the 20 said valves is bounded by a helical ramp in order to close the admission ports 48, 49 during a greater or less portion of each revolution, and in proportion to the work required. One of the said valves operates during 25 forward running and the other during reverse running of the engine.

Since the steam is best utilized by its admission into the motor at the boiler pressure, calculations for the adjustment for a given 30 power show that the steam is to be admitted during a certain angle of rotation whereas the remainder of the stroke is employed for expansion, in such manner that exhaust takes place at a pressure which is near atmospheric 35 pressure.

To change the direction of running, I utilize a distributing element 50 which may be 40 rotated by a hand wheel 16 mounted on a tubular shaft 15 in which is slidably the rod 17 having thereon the valves 13 and 14 and ending in a lever 18 opposed by the action of the spring 19. Said spring is mounted on a rod 20 upon which is screwed the spring-regulating nut 21, said nut being graduated 45 by experiment and serving to control the displacement of the tumblers instigated by the governor 25.

The said governor is provided with a movable rod 24 provided with a shoulder co- 50 operating with the ball-levers. Said rod is preferably provided with longitudinal grooves whereby all effect of the steam pressure is obviated. A hand wheel 27 controls a valve 26 for closing the steam inlet, for example when the motor is reversed. On the 55 end of the shaft 5 is disposed a metallic stuffing-box arrangement 32 comprising a ring provided with a collar which latter is in contact with the surface of the end portion 9. To prevent an excessive bearing surface which might cause an adhesion capable of 60 rotating the said ring upon the stationary crankshaft, suitable balls whose diameter is equal to the depth of the recess containing 65 the same are interposed between the said

collar and the end surface. The square packing ring ensures fluidtightness, so that the speed of rotation of the whole becomes diminished. It should be observed that the known types of stuffing box cannot be employed, as the packing would require a frequent removal. 70

The steam inlet is controlled by a gate valve 34. The motor is provided with the sight-feed oilers 35, 36 of which the first 75 serves to supply oil to the current of steam and the second to lubricate the ball-bearings of the internal cylinders through the ducts 42, 43. The oil is contained in the tank 37 which is placed under pressure through a 80 tube 38 having a check valve at the top. Said valve is lowered and opens when the plug 39 is screwed on, and closes automatically before the said plug is entirely removed, so that the device can be filled during the 85 running. The cock 40 serves to evacuate any condensate produced in the tank 37.

The plates 55, 56 are pivoted to the cylinder 1 and are slidably mounted in the rockers 57, 58 mounted on the cylinders 3, 4 90 and enabled to oscillate thereon. Steam is admitted through the conduits 51, 53, 54, 59 which are disposed in pairs on each side of the said plates. In each pair, one of the said conduits corresponds to a given direction of 95 running. The exhaust takes place through the same conduits when they come opposite the recesses 60, 61 of the distributor which connects them with the interior of the engine casing through the apertures 62, 63 of the 100 housing 52.

The operation is as follows. With the cock 26 in the closed position, the gate valve 34 is opened, and the pressure will now prevail in the lubricating device which is allowed to heat up for a few seconds. The outlets at 35 and 36 are regulated, and the valve 26 is then slowly opened. The condensed water is circulated along with the steam through the conduits and into the motor cylinders, and the motor will start at once, even when cold. No inconvenience is to be apprehended from the effects of the condensation at the start, as the evacuation can always take place through the exhaust which 115 is constantly open.

The steam entering through the hollow shaft 5 into the said valves will flow through one or the other of the ports 48, 49 into the conduits 59, 51 for one direction of running 120 or into the conduits 54, 53 for the opposite direction. This admission begins at the instant at which the plate 55 or 56 passes the point of tangency of the two cylinders and is cut off at a later point according to the position of the said discs.

After expansion, the steam can escape at the other side of the plate through the conduits 53 and 54 for forward running, or through the conduits 51 and 59 for reverse 130

running, and with a constant flow, since in each case the respective conduits are constantly connected by the recesses 60 or 61 and the apertures 62 or 63 with the interior of the main casing 6. Since the spring 19 regulates the operating rate for which the engine has been designed, the inlet of steam is automatically limited by the operation of the valves 13, 14. Inasmuch as the steam expands to the maximum, a high degree of efficiency will be thus obtained, and this may be further increased by connecting the exhaust with a condenser.

Having described my invention what I claim as new and desire to secure by Letters Patent is:—

In a rotary engine of the type described the combination of a hollow fixed shaft, a rotor adapted to rotate concentrically about said shaft, fluid distributing means concentrically disposed on said rotor, a non-rotatable spiral valve positioned within said means cooperating therewith, a control rod for said valve extending through said fixed shaft, and means for longitudinally displacing said control rod whereby the point of admission of said means is variable at will.

In testimony whereof I have hereunto affixed my signature.

CLAUDE DREVET.
